UNITED STATES PATENT OFFICE.

WALTER L. INGRAM, OF MONTGOMERY, ALABAMA.

AUTOMOBILE SIGNAL SYSTEM.

Application filed October 5, 1922. Serial No. 592,492.

To all whom it may concern:

Be it known that I, WALTER L. INGRAM, a citizen of the United States, and a resident of the city and county of Montgomery, State 5 of Alabama, have invented certain new and useful Improvements in Automobile Signal Systems, of which this is a specification, reference being had to the accompanying drawing, forming part hereof.

10 My invention relates to apparatus whereby the driver of an automobile may signal to others his intention, as to turn right or left, stop, etc. The object of the invention is to provide novel, efficient and reliable apparatus for this purpose, and particularly to 15 utilize the power of the usual internal combustion motor to operate the signals.

In the drawing, which shows the invention in its elements, 1 is a small tube led 20 off from a spark plug, such as those known as priming plugs or as employed with the engine-operated tire pumps. The tube may be similarly attached to the exhaust manifold but I prefer to use the plug. Pipe 1 leads to 25 a small pump as at 2, containing a two-diameter piston as at 4 and 5, and which may be normally restrained by a spring 6. This pump, not different from those employed for pumping tires, and which may be variously 30 modified, feeds a storage tank 3, of suitable size. From the tank pipes are carried to the signal means. One pipe, 7, controlled through a valve at 8, arranged to be operated by depression of the brake pedal 9, supplies 35 pipe 10, 10, and through it a cylinder 11, the plunger of which, 12, is arranged to operate the stop signal lever 13. Obviously, the opening of valve 8 by depression of the 40 brake pedal will cause plunger 12 to lift the stop signal lever 13 and the attached stop signal member 14, preferably bearing the word "Stop" as at 15. Another pipe 16 is taken to a two-way valve 17 by means 45 of which the signals for right and left may be controlled. Suitable pipes are taken to appropriate cylinders (hidden in the figure by the cylinder 11, but of identical character) in the drawing pipe 18 controlling the left and pipe 19 the right signal. I provide 50 a normally visible back-ground as at 21, which is preferably a plate of ground glass of green color, behind which I provide a small lamp as at 22. The normal field or back-ground is, therefore, a green area. The 55 ordinary signals, as for right and left, are transparent or translucent mediums, discs

in the figure, provided with appropriate lettering. As drawn the "left" signal is shown in operative position obscuring the normal back-ground. 20 is the signal lever, 23 the signal member; the structure for the "right" signal being identical, but, of course, not shown in the figure.

With the apparatus as indicated the left or right signals are given by displaying 60 black letters on a green ground, the one or the other legend as the two-way valve is turned, or none if the valve is set to close both supply pipes. The stop signal I provide with a red legend and with either a 65 clear or opaque ground. It, therefore, displays the word "Stop" in red, giving a distinctly different appearance from the normal right and left legends. I find that with a 70 clear red lettering it shows clearly even though it is illuminated by the normal green light which comes through the back-ground. The signals are, of course, quite visible in day light without the need of the lamp but at night the lamp is a necessity.

75 A feature of the invention as disclosed is that regardless of whether either or none of the other signals are in operative position the "Stop" may be displayed at will, or even without volition by the driver, for depression of the brake pedal will operate the stop signal and obscure whatever signal is then displayed by the red lettered word "Stop". In practice I find the stop signal 80 is quite as effective if displayed over a right or left as if displayed alone—whatever light comes through the red lettering giving an efficient signal, clear and unmistakable.

85 I have shown an elementary apparatus merely to illustrate the points of the invention. The signal apparatus will, of course, be provided with suitable casing and situated at such places on the automobile as may be desired. The two-way valve is to be located within easy reach of the driver and is, of course, the equivalent of two independent valves, or of independent control of the 90 right and left pipes.

95 It will be understood, of course, that while I prefer to employ a pressure system, as shown, for the reason that as high a pressure as desired may be had, yet it is possible to utilize many of the features of the invention by a vacuum control, vacuum created 100 as in the well known vacuum feed gasoline systems. This is particularly the case with regard to the arrangement of normal right 105

and left signals arranged to be occluded by the stop signal regardless of which is then being displayed.

Having described my invention, what I claim is:

In a signal system of the class described, in combination with an internal combustion motor, movable and translucent signal members controlled by said motor arranged to be moved jointly or independently, a normally illuminated background against which said signal members may be displayed, and

said signals so arranged that the one of them intended as a stop signal is visible through either of the other signal members when the two are simultaneously against said background, substantially as set forth.

Witness my hand at Montgomery, Ala., this October 2, 1922.

WALTER L. INGRAM.
